UNITED STATES PATENT OFFICE.

THOMAS W. CAREY, JR., OF NEW ORLEANS, LOUISIANA.

OAR-LOCK.

No. 926,847.

Specification of Letters Patent.

Patented July 6, 1909.

Application filed August 15, 1906, Serial No. 330,671. Renewed October 28, 1908. Serial No. 459,935.

To all whom it may concern:

Be it known that I, THOMAS W. CAREY, Jr., a citizen of the United States, and a resident of the city of New Orleans, in the parish of Orleans and State of Louisiana, have invented a new and Improved Oar-Lock, of which the following is a full, clear, and exact description.

My invention relates to oar-locks, and the purpose of the invention is to improve upon the construction of oar-lock for which application for Letters Patent was made by me October 19th, 1905, Serial No. 283,419, and allowed June 2, 1906, the improvements consisting in the material simplification and lightening of the construction without detracting from its strength, together with an improved means for regulating the rotation of the oar in its bearings, and for regulating the dip of the oar.

It is also a purpose of the invention to render it possible to assemble or to disconnect the various parts much more conveniently and expeditiously than under the allowed construction above referred to.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a side elevation of a portion of the body of a boat and its outrigger, and a side elevation of the improved oar-lock in position on the outrigger, the sweep or oar being in section; Fig. 2 is an enlarged sectional side elevation of the oar-lock, the oar or sweep being in transverse section; Fig. 3 is a section taken practically on the line 3—3 of Fig. 2; Fig. 4 is a section taken practically on the line 4—4 of Fig. 2; and Fig. 5 is a vertical section through a modified form of the socket member of the device, the section corresponding to that shown in Fig. 2.

A represents a side of a boat and B the outrigger attached thereto, longitudinally upon which outrigger the base plate 10 of the improved oar-lock is bolted or otherwise secured. The body C of the oar-lock is a ring body and is made in two sections, a lower section c and an upper section c', the two sections being connected at one of their opposing ends by a hinge 11, as is shown in Figs. 1 and 2. At the opposite end of each

section correspondingly slotted horizontal lips are integrally formed, adapted when the sections of the said ring body are closed to engage one with the other, and the upper lid 60 is designated as 12 and the lower one as 13. A bolt 14 provided with a wing nut 15 is pivoted in the slot of the lower lip 13, and when the sections of the ring body are to be held closed the bolt 14 is carried vertically 65 upward into the slot in the upper lip 12 and the nut 15 is screwed to a firm bearing upon said lip as is best shown in Fig. 2.

At the hinge end of the lower body section c a bearing surface 16 is provided in the form 70 of a flat disk, as is particularly shown in Fig. 2, and from the center of said bearing disk 16 a pintle 17 extends horizontally outward, and said pintle is provided with an external annular groove 18 and a rounded outer end 75 or head 19. A band D is adapted to turn in the ring body C, and said band is preferably much wider than said body so as to extend beyond the side faces of the body. The band D is firmly attached to the handle of 80 the oar or sweep E by means of screws or their equivalents, and the said oar-band is provided with a centrally-located exterior rib 20 that extends into a corresponding groove 21 in the inner face of the ring body 85 C when the sections of the body are closed upon the said band as is also shown in Fig. 2.

A socket F is provided for the ring body C. This socket consists of a vertical member 22 and a horizontal member 23, both of which 90 members have chambers therein, but the chambers of the two members do not intersect, and the chamber of the vertical member 22 extends through from top to bottom. The upper end of the chamber in the member 95 22 of the socket F is conical to receive a cone bearing nut 25, which is secured upon the upper threaded end of the bolt 26, the lower end of which bolt is likewise threaded. After the bolt has been passed up through 100 the said chamber in the member 22 of the socket, a cap nut 27 is screwed upon its upper end so as to hold the conical nut firmly to its seat. This conical nut serves to cause the said socket F to turn more or less loosely 105 on the bolt 26 which is the pivot pin for the said socket.

At the lower end of the vertical member 22 of the socket F a large horizontally located circular chamber is formed, in which chamber a lining 26^a of hard metal is located, as is shown in Fig. 2, and the bottom of this lower

circular chamber is open, but said chamber is closed, when the bolt 26 is in position in the socket F, by means of the aforesaid base plate 10, which is attached to or constitutes 5 an integral portion of the bolt 26, and just above said base plate 10 a conical section 10^a is formed on the said bolt, as is also shown in Fig. 2.

The lower portion of the bolt 26, or that 10 portion which is below the base plate 10 is adapted to pass through the outrigger B or through the gunwale of the boat, and is held in its set position by a nut 28 followed by a locking nut 29; and in the chamber at the 15 bottom of the said vertical member 22 of the socket F balls or rollers 30 are usually placed, which have bearing against the cone section 10^a of the bolt 26, the lining 26^a of the lower chamber in said socket and the upper face of 20 the base plate 10, so that the said socket F may turn around the bolt 26 with the least amount of frictional contact between its bottom surface and the said base plate. But if 25 desired the ball bearing chamber may be omitted and the base plate 10 may be brought to a direct bearing with the bottom of the socket F, as is shown in Fig. 5.

A chamber in the horizontal member 23 of the said socket F is adapted to neatly receive 30 the pintle 17 extending from the ring body C, as shown in Figs. 2 and 3, but the chamber in said horizontal member 23 of the socket F is provided with a pocket 31 at its bottom portion, which communicates 35 directly with said chamber, and a fin 32 formed integral with or attached to the pintle 17 extends down into said pocket. This fin is adapted to regulate the dipping action of the oar and is used in connection with opposing 40 screws 33, which are made to enter the pocket 31 from opposite sides of the said socket member 23 as shown in Fig. 3, and each screw is provided with a controlling nut 34.

45 The pintle 17 of the ring body C is held to turn in the chamber of the socket member 23 by passing a bolt 35 through the said member 23, and through the groove 18 in the said pintle as is shown in Figs. 2 and 4, which 50 bolt 35 is provided with a head at one end and a nut at the opposing end.

A regulating bolt 36 is passed through a slot 36^a in the upper central portion of the upper section c' of the ring body C, which 55 regulating bolt is provided with a rectangular head 37, loosely fitted in the groove 21 in the said ring body, and is further provided at its outer end portion with a nut 38 and accompanying washer. The head of the bolt 36, 60 which is adjustable in the slot 36^a, is adapted to be engaged by a pin 39 extending from the rib 20 on the oar-band D, and when such an engagement takes place it signifies to the oarsman that the blade has reached the proper 65 position for planting or dipping the same

in the water to make a stroke, and said time is regulated by the adjustment of the said bolt.

It is obvious that the improved oar-lock is well adapted for the purpose intended, since 70 the ring body C is capable of turning in the socket F and the socket F turns around its pivot bolt 26, while the oar or sweep has limited rotary movement in said ring body C.

Having thus described my invention, I 75 claim as new, and desire to secure by Letters Patent,—

1. In an oar lock, a ring body, an oar band mounted to turn in the ring body, adjustable means for limiting the degree of rotation of 80 the oar band, a pintle extending from the ring body, a socket comprising a vertical and horizontal member, the horizontal member having a chamber for receiving the pintle of the ring body, said pintle having an annular 85 groove and a bolt traversing the horizontal member and extending into the groove whereby to retain the pintle in the chamber, and a pivoted bolt passing through the vertical member of the socket and upon which 90 said socket turns.

2. In an oar-lock, a sectional ring body, means for connecting said sections, an oar-band mounted to turn in the ring body, devices for adjustably limiting the degree of 95 rotation of the said oar-band, and a pintle extending from a section of said ring body, of a socket comprising a vertical and a horizontal member, the horizontal member being provided with a chamber into which the pintle of the ring body extends and turns, means for retaining the pintle in the chamber of the 100 said horizontal member of the socket, an extension from the said pintle within its receiving chamber, adjustable stops which enter 105 said chamber at opposite sides of said extension to regulate the dipping action of the oar, and a pivot bolt passed through the vertical member of the socket, around which bolt the 110 said socket turns.

3. In an oar-lock, a sectional ring body, means for connecting said sections, an oar-band mounted to turn in the ring body, devices for adjustably limiting the degree of rotation of the said oar-band, and a pintle extending from a section of said ring body, of a socket comprising a vertical and a horizontal member, the horizontal member being provided with a chamber into which the pintle 115 of the ring body extends and turns, means for retaining the pintle in the chamber of the said horizontal member of the socket, an extension from the said pintle within its receiving chamber, adjustable stops which enter 120 the said chamber at opposite sides of the said extension to regulate the dipping action of the oar, a pivot bolt adapted to be fixed to an outrigger on the gunwale of the boat, which bolt passes loosely through the vertical member of the socket, a conical bearing 125 130

nut carried by the upper end of the bolt, engaging with a conical seat in said vertical member, a cap nut for the upper end of the said bolt, a base plate adapted for engagement with the lower face of the said socket, and means for attaching the lower end of the bolt to the gunwale on an outrigger of the boat.

4. In an oar-lock, a sectional ring body, means for connecting said sections, an oar-band mounted to turn in the ring body, devices for adjustably limiting the degree of rotation of the said oar-band, and a pintle extending from a section of the said ring body, 15 of a socket comprising a vertical and a horizontal member, the horizontal member being provided with a chamber into which the pintle of the ring body extends and turns, means for retaining the pintle in the chamber of the 20 said horizontal member of the socket, an extension from the said pintle within its receiving chamber, adjustable stops which enter the said chamber at opposite sides of the said extension to regulate the dipping action of 25 the oar, a pivot bolt adapted to be fixed to an outrigger on the gunwale of the boat, which bolt passes loosely through the vertical member of the socket, a conical bearing nut carried by the upper end of the bolt, engaging with a conical seat in said vertical member, a cap nut for the upper end of said bolt, a base plate secured to said bolt near its lower end, which base plate is adapted to

close the lower portion of the chamber formed at the bottom of the vertical member of the socket, the said bolt being likewise provided with a conical section immediately above the base plate, balls located in the said chamber, having engagement with the wall thereof, the conical section of the bolt 40 and the bearing plate, and means for securing the lower end of the said bolt to an outrigger on the gunwale of a boat.

5. In an oar-lock, a sectional ring body, means for securing the sections together, an oar-band having limited rotary movement in 45 said ring body, adjustable means for regulating the extent of rotation of the oar-band in the body, a socket comprising a vertical and a horizontal member, an extension from 50 a section of the ring body mounted to turn in said horizontal member of the socket, means for retaining said extension in said member of the socket, means for regulating the rotation of the extension from the body 55 in the socket, an attaching bolt for the oar-lock around which the said socket turns, and means for increasing or decreasing the tension between the socket and the said bolt.

In testimony whereof I have signed my name to this specification in the presence of two subscribing witnesses.
